UNITED STATES PATENT OFFICE.

CHRISTIAN A. RITTMAN, OF SANDUSKY, OHIO.

CHALKING DEVICE.

SPECIFICATION forming part of Letters Patent No. 587,863, dated August 10, 1897.

Application filed June 24, 1896. Serial No. 596,698. (No model.)

To all whom it may concern:

Be it known that I, CHRISTIAN A. RITTMAN, a citizen of the United States, and a resident of Sandusky, county of Erie, and State of Ohio, have invented certain new and useful Improvements in Line-Chalking Devices, of which the following is a specification, the principle of the invention being herein explained and the best mode in which I have contemplated applying that principle, so as to distinguish it from other inventions.

The annexed drawings and the following description set forth in detail one mechanical form embodying the invention, such detail construction being but one of various mechanical forms in which the principle of the invention may be used.

In said annexed drawings, Figure I represents a side elevation of my improved line-chalking device; Fig. II, a view partly in longitudinal cross-section and partly in elevation; Fig. III, an end elevation; Fig. IV, a perspective view of one end of the device, showing a modification of the manner of attaching the chalk; and Fig. V is a perspective view representing the manner of manipulating the device.

The device consists of a handle A, constructed of wood, turned to a suitable form for being gripped by the hand and formed with an enlarged portion or flange a, the edge a' of which is rounded off. The flange a surrounds a central cylindrical recess a², extending part way into the handle. A central longitudinal bore a³ extends into the opposite end of the handle and communicates with the recess a² by means of a central bore a⁴ of smaller diameter than that of a³ and forms the shoulder a⁵. A slot a⁶ is cut into the end 40 of the handle, traversing it centrally and cutting the bore a³.

A spindle C, of slightly smaller diameter than the bore a⁴, traverses the handle A and extends through and beyond the recess a².

Upon the end of the spindle C is mounted the spool B of slightly smaller diameter than that of the recess a², formed at its upper end with the flange b and two small lateral recesses b'. The spool in turn mounts an annular cylinder of chalk D of a little less altitude than the distance from the inner side of

the flange b and the opposite end of the spool, forming the shoulder b². The one end of the chalk is formed with a projecting boss d, upon which is mounted a thin sheet-metal cup E, whose face is perforated with a circular series of indentations forming small lips e, projecting downwardly into the chalk and which serve to prevent the said cup from rotating upon the chalk. The cup E is further provided with two small lips e', which project into the lateral recesses in the spool b', and thus prevent the cup E and the attached chalk D from rotating upon the spool. A thin sheet-metal cup F covers the flange b and protects the wood from damage. The spindle C journals the spool and chalk and is pierced near its extreme end by a small split pin G, thereby preventing the retraction of the spindle.

The opposite end of the spindle is provided with a handle c, formed with an eye c', a circularly-enlarged portion c² and a lip c³, the eye portion projecting through one side of the slot a⁶, the lip projecting into the other side, and the portion c² moving in the bore a³, the eye itself clearing the wooden handle. A spring H is interposed between the shoulder a⁵ and the enlarged portion c² of the small handle c and holds the chalk against the flange a.

In the modification of the manner of attaching the chalk to the spool the flange b is omitted and the lip e' projects into a downwardly and then laterally and upwardly recessed slot b⁴.

In operating the device the handle A is gripped in the hand, the little finger inserted through the eye c', the line inserted in the line-opening between the flange a, the chalk D resting against the shoulder b². The operator passes the instrument along the line, which has previously been stretched taut, the helical construction of the line acting like a screw and rotating itself, exposing all its surface to the chalk, while the chalk at the same time rotates about the spindle C and submits all parts of the surface of its base to an equal or nearly equal amount of abrasion. As the chalk abrades the spool enters the recess a', thus compensating for wear.

In case of the presence of knots in the line a slight pressure of the little finger will neu-

tralize the pressure of the chalk against the line and permit the said chalk to retract and the obstruction to pass through.

When it is desired to remove or replenish the chalk, the split pin e^2 is removed from the spindle, permitting the removal of the spool, from which the chalk can be slid off or on, disengaging or engaging the lips b' .

In the modified form shown in Fig. IV the chalk with its attached cup need merely to be pushed downwardly, then rotated a short distance, and then pulled off the spool, as will be readily understood.

The form shown in Fig. II is my preferred form.

Other modes of applying the principles of my invention may be employed for the mode herein explained. Change may therefore be made as regards the mechanism thus disclosed, provided the principles of construction set forth respectively in the following claims are employed.

I therefore particularly point out and distinctly claim as my invention—

1. In a line-chalking device, the combination of a fixed surface, a rotatable surface, one of said surfaces being a chalk-surface, said surfaces forming an annular line-opening and means adapted to vary the width of said opening, substantially as set forth.

2. In a line-chalking device, the combination of a fixed and a rotatable surface, one of which is a chalk-surface, said rotatable surface mounted upon a spindle, means adapted to confine said rotatable surface on said spindle, said surfaces forming an annular line-opening, means adapted to retract said confining means, whereby said surfaces are permitted to retract, substantially as set forth.

3. In a line-chalking device, the combination of a handle, a fixed surface at the end of said handle, a rotatable surface, said surfaces forming an annular line-opening, said rotatable surface mounted upon a spindle, means adapted to cause said surfaces to approach each other, and means adapted to retract said spindle whereby said surfaces are permitted

to retract, one of said surfaces being a chalk-surface, substantially as set forth.

4. In a line-chalking device, the combination of a handle, a non-chalking surface at the end of said handle, a chalk-surface contiguous to said non-chalking surface, said surfaces forming an annular line-opening, a spring adapted to cause said surfaces to approach each other, one of said surfaces being rotatable and mounted upon a spindle provided with means for confining said surface thereon, and means adapted to release said confining means, whereby said surfaces are permitted to retract, substantially as set forth.

5. In a line-chalking device, the combination of a piece of chalk mounted upon a spool, said spool mounted upon a retractable spindle, a washer having binding engagement with said chalk and said spool, whereby the said chalk is rotatively fixed relatively to said spool; an opposing surface, said chalk and surface adapted to yieldingly impinge upon and rotate relatively to each other, substantially as set forth.

6. In a line-chalking device, the combination of a cylindrical piece of chalk, mounted upon a spool, a handle formed with a longitudinal bore and a recess adapted to receive said spool, and an axial slot traversing the handle, and further formed with a flat surface concentric with the recess; a spindle formed with a handle at right angles, the said spindle traversing the longitudinal bore of the handle and journaling the spool and chalk; a spring located in the longitudinal bore and adapted to hold the chalk against the surface, and means for preventing the dislodgment of the spool from the spindle, substantially as set forth.

In testimony that I claim the foregoing to be my invention I have hereunto set my hand this 18th day of June, A. D. 1896.

CHRISTIAN A. RITTMAN.
